UNITED STATES PATENT OFFICE.

WILLIAM PEPPERLING, OF AITKIN, MINNESOTA.

STEAM-ENGINE.

SPECIFICATION forming part of Letters Patent No. 625,195, dated May 16, 1899.

Application filed December 22, 1898. Serial No. 700,069. (No model.)

To all whom it may concern:

Be it known that I, WILLIAM PEPPERLING, a citizen of the United States, and a resident of Aitkin, Aitkin county, State of Minnesota, 5 have invented certain new and useful Improvements in Steam-Engines; and my preferred manner of carrying out the invention is set forth in the following full, clear, and exact description, terminating with claims particularly specifying the novelty.

This invention relates to compound steam-engines, more especially of that type embodying a multiple cylinder; and the object of the same is to produce an engine wherein the exhaust from one cylinder is used for driving the piston in another.

To this end the invention consists in the construction of cylinders, pistons, and ports illustrated in the accompanying drawing, 20 showing a section of my improvement, and as fully described and claimed below.

Referring to the drawing by letters and figures, C designates as a whole the cylinder, here shown as in three members end to end, 25 and specifically designated by supernumerals 1, 2, and 3, and P similarly indicates the pistons in these cylinders, all mounted on the piston-rod R, moving through suitable stuffing-boxes where shown.

30 S is the steam-chest, V the valve therein, and E the rod leading from such valve to a suitable eccentric or other valve-operating mechanism. (Not shown.)

Thus far and also including the common 35 steam-inlet I and exhaust X no novelty is claimed for the construction shown.

Coming now more particularly to my present invention, the live steam is admitted at, say, one hundred and fifty pounds pressure 40 through 1 to the port 2, leading to the right end of the cylinder C³ and entering at 8 behind the piston P³, which is about to move in the direction of the arrow. The exhaust from the other end of this cylinder leaves it at 4, 45 passes along port 5 through a Y 6, up through opening 7 in the valve V, and along the outlet 8 to main exhaust X. Hence on this stroke the right-hand cylinder receives steam direct and exhausts direct. The rod R causes a simultaneous movement of the left-hand piston P'. Here the moment the valve V moves to the position illustrated the steam, which has

just been used on the preceding stroke and is now down to, say, forty pounds pressure, passes out at 11 along port 12 through opening 13 in the valve V, through a Y 14, along port 15, and in behind the piston P' at 16, thus instantaneously equalizing the pressure on opposite sides of this piston and by the increase of volume reducing such pressure to, say, 60 thirty-nine. The inlet for the intermediate cylinder C² is taken from the outlet of the left-hand cylinder C'. Steam flowing through port 12 and Y 14 branches at the latter point and some of it passes along port 21 to the 65 point 22 behind piston P, thus further increasing the volume and reducing the pressure in all these parts to, say, thirty-eight.

Meanwhile the exhaust from in front of this piston leaves the cylinder C² at 23, passes along port 24, and joins the main exhaust at 70 Y 6. The thirty-eight pounds at the right of piston P² will now move it to the left with a force which, through rod R, is added to that set up by the piston P³, and as the pressure on opposite sides of piston P' continues equal, by reason of the port connecting those sides, this piston now does no work. As the intermediate piston P² moves to the left the steam area increases and necessarily the pressure falls from 80 thirty-eight to, say, nothing at the completion of the stroke; but this does not affect the piston P' because the reduction of pressure is taken equally from both sides thereof by means of the connecting-ports described. 85

Thus it will be seen that at the beginning of this stroke the left-hand piston is equalized as to pressure; but the steam exhausted therefrom is given an opportunity to work on expansion in the intermediate cylinder, and it 90 will be evident that on the reverse movement (which of course takes place through proper shifting of the valve V) the reverse operation will ensue. Hence all steam is used twice in this arrangement—the first time at boiler-pressure in one of the extreme cylinders, expanded and equalized in the other, and under expansion in the intermediate cylinder, and the second time on the reverse stroke, when the live steam just used now expands 95 and equalizes itself in the one extreme cylinder and expands in the intermediate cylinder, while the other extreme cylinder is acting under a fresh charge of live steam. It

will be unnecessary to amplify the advantages resulting from this arrangement, because the expansive power of steam is so well understood. My object is to give full play 5 to this power and use it to the fullest advantage with the simplest construction of parts.

What is claimed as new is—

1. In a compound engine, the combination with three pistons of equal diameter moving 10 in unison in three cylinders arranged in tandem, a steam-chest, a valve therein having two openings, a main exhaust with which said openings register alternately, and two ports on either side of such exhaust; of ports 15 leading from the outer ends of the extreme cylinders to the endmost ports in the steam-chest, and other ports leading from the next innermost ports in the steam-chest, each to the inner end of one extreme cylinder and through 20 a branch to the remote end of the intermediate cylinder, all as and for the purpose set forth.

2. In a compound engine, the combination with three cylinders of equal diameter end to

end and in tandem, a common rod, and three 25 pistons thereon in their respective cylinders; of main ports leading from the outer ends of the extreme cylinders, other ports leading from their inner ends to points adjacent a common exhaust, branch ports leading from said 30 latter ports across each other to respectively remote ends of the intermediate cylinder, and means for alternately connecting one main port with the supply and the other with the remote end of the intermediate cylinder and simultaneously connecting said "other" port of the cylinder receiving direct supply with the main exhaust and with the opposite end of the intermediate cylinder, all as and for the purpose set forth. 40

In testimony whereof I have hereunto subscribed my signature this the 19th day of December, A. D. 1898.

WILLIAM PEPPERLING.
